COMBINED BOTTLE CAP AND POURING DEVICE

Adolph P. Berman, New York, N. Y.

Application December 13, 1954, Serial No. 33,524

Term of patent 7 years

(Cl. D58—26)

The figure is a perspective view of a combined bottle cap and pouring device showing my new design.

The side of the design not shown is the same as the side shown.

I claim:

The ornamental design for a combined bottle cap and pouring device, as shown and described.
